US00D805927S

(12) **United States Design Patent** (10) Patent No.: **US D805,927 S**
(45) Date of Patent: **** Dec. 26, 2017**

(54) **THERMOMETER**

(71) Applicant: **KONINKLIJKE PHILIPS N.V.**
Eindhoven (NL)

(72) Inventors: **Frank Verbrugge**, Rosmalen (NL);
Guy Anthony Brown, Haarlem (NL)

(73) Assignee: **KONINKLIJKE PHILIPS N.V.**
Eindhoven (NL)

(**) Term: **15 Years**

(21) Appl. No.: **35/501,399**

(22) Filed: **Feb. 18, 2016**

(80) **Hague Agreement Data**

Int. Filing Date: **Feb. 18, 2016**
Int. Reg. No.: **DM/089595**
Int. Reg. Date: **Feb. 18, 2016**
Int. Reg. Pub. Date: **Aug. 19, 2016**

(30) **Foreign Application Priority Data**

Aug. 25, 2015 (EM) 002759746-0001

(51) LOC (10) Cl. **10-04**

(52) U.S. Cl.
USPC **D10/57**

(58) **Field of Classification Search**
USPC D10/57
CPC G01K 1/00

See application file for complete search history.
